CLAIM

The ornamental design for eyeglass lens, as shown and described.

DESCRIPTION

FIG. 1 is a perspective view of the new design for an eyeglass lens;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a front perspective view of eyeglass lens with environment.

The broken lines in the figures show portions of the eyeglass lens that form no part of the claimed design.

1 Claim, 7 Drawing Sheets
